UNITED STATES PATENT OFFICE.

WILLIAM H. GRAHAM, OF ST. LOUIS, MISSOURI.

DESIGN FOR A SINK-TRAP.

SPECIFICATION forming part of Design No. 21,529, dated May 10, 1892.

Application filed December 28, 1891. Serial No. 416,379. Term of patent 14 years.

To all whom it may concern:

Be it known that I, WILLIAM H. GRAHAM, of St. Louis, Missouri, have invented and produced a new and original Design for Traps, 5 of which the following is a specification, reference being had to the accompanying drawings, making part of this specification, and in which—

Figure 1 is a side elevation of a trap, showing my design; and Fig. 2, an edge elevation of the same, the two views being desirable to better illustrate the design.

The leading feature of the design consists in the general form of the body or main portion of the trap.

A represents said body or main portion. It is substantially of an annular form, saving as modified by the attachment thereto of the tubular portions B, C, and D, which are re-

spectively the inlet, the outlet, and the vent 20 of the trap and which project from the body substantially as follows: the inlet rising from the top of the body, the outlet extending laterally therefrom, and the vent being arranged between the inlet and outlet and curving upward and laterally from the body and terminating above and substantially parallel with the outlet.

What I claim is—

The design for a sink-trap, as herein described and shown.

Witness my hand this 19th day of December, 1891.

WILLIAM H. GRAHAM.

Witnesses:

C. D. MOODY,
A. BONVILLE.
